(57) **CLAIM**

The ornamental design for an analysis chip for biochemical inspection machine, as shown and described.

DESCRIPTION

FIG. 1 is a top-front-right perspective view of an analysis chip for biochemical inspection machine showing my design;

FIG. 2 is a top-rear-left perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof; and,

FIG. 8 is a bottom plan view thereof.

The dash-dash broken lines, the area within the dash-dash broken lines, and the areas bounded by the dash-dash broken lines and solid lines depict portions of the analysis chip for biochemical inspection machine that form no part of the claimed design.

The dot-dash broken lines depict the boundaries of the claimed design and form no part thereof.
